REST PROMOTING APPLIANCE

Leo M. Hoey, San Antonio, Tex.

Application January 16, 1934, Serial No. 706,886

2 Claims. (Cl. 128—164)

This invention relates to a multiple part accessory or appliance principally designed for use by a human being and constructed with the end in view of providing the user with comforting means for excluding light and sound and promoting thorough rest.

Broadly and briefly described the preferred embodiment of the invention embodies a headgear or harness characterized by selectively usable adaptation means serving in one instance to cover the eyes to substantially exclude light, to plug the ears to partially exclude annoying sounds and noises, and which also serves to support the chin to keep the mouth closed in order to promote proper nose breathing and to overcome snoring.

In reducing the invention to practice I have selected and coordinated the features of the construction in such a manner as to permit them to be employed simultaneously or individually as occasion demands.

Other features and advantages of the invention will become more readily apparent from the following description and drawings.

In the accompanying illustrative drawings wherein like numerals are employed to designate like parts throughout the views:

Figure 1 is an elevational view showing the complete assembly forming the headgear or harness and showing the manner in which the complementary parts thereof are worn.

Figure 2 is a front elevational view illustrating principally the adjustable framework whose principal function is to hold removable ear plugs or stopples in place.

Figure 3 is a top plan view of the arrangement depicted in Figure 2.

Figure 4 is a detail section on an enlarged scale taken on the plane of the line 4—4 of Figure 2.

Figure 5 is a fragmentary elevational view disclosing one of the adapter elements for holding a companion ear plug in place.

Figure 6 is an elevational view of the light excluding eye shield unit.

Figure 7 is an elevational view of an additional accessory or unit which may be differentiated as the chin supporting unit.

Figure 8 is a detail view of the noseguard constituting a feature of the eye shield.

Figure 9 is a section taken approximately on the plane of the line 9—9 of Figure 5.

Figure 10 is a detail view partly in section and partly in elevation showing the construction of one of the improved ear plugs or stopples.

Figure 11 is a top plan view of the stopple shown in Figure 10.

As before intimated the harness is composed of a plurality of parts or individual accessories. Although these may be well described as a unit I prefer to distinguish each unit by primary numerals. For instance as shown in Figures 2 and 3 the numeral 12 designates the head gear. The numeral 13 in Figures 1 and 7 indicate the chin supporting means or unit. The numeral 14 designates the light excluding eye shield or unit. For sake of clearness of description the units will be described individually since in practice they may be used collectively or separately as occasion requires. All three of these units, however, that is the parts 12, 13 and 14 constitute what may be broadly referred to as a harness and in practice they may be joined together in such manner as to permit separate use without subjecting the parts to accidental displacement when not in use.

Analyzing the head gear 12 it will be observed that this is principally made up of bent parts formed of wire metal or equivalent means. It comprises a pair of companion semicircular bows and each bow is made up of adjustable connection portions or sections. The bows are disposed at right angles to each other and that bow which extends across the crown of the head is composed of the distinguishable parts 15 and 16 whose overlapping ends are slidably united by a sleeve-like coupling 17. That bow which partially encircles the back of the head is made up of the sections 18 and 19 whose overlapping ends are also slidably joined together by a similar coupling sleeve 20. These bows are primarily adapted to hold the adapter or ear frames 21 in proper position.

The frame as shown in Figure 5 is shaped to partially embrace the adjacent ear and it includes a resilient retention or presser element 22 shaped to fit into the ear somewhat in the manner illustrated in Figure 1. This retainer 22 is also shaped in a manner to conveniently hold the complementary ear plugs or stopples 23 in place.

The numeral 24 in Figure 5 is merely a brace or connective strap which reinforces and retains the proper shape of the ear adapter 21. Incidentally, the wire forming the adapter is preferably wrapped as indicated at 25 to afford the requisite pad like action. The wrapping may be rubber or fabric, the thought being merely to overcome undue pressure against the head and to minimize discomfort.

The unit 13 comprises a head encircling strap 26 which is preferably elastic and this is attached to a chin holder 27 which may be conveniently

referred to as a stirrup. As before stated this part 13 may be made for permanent attachment to the head gear if and when occasion requires.

The light excluding eye shield unit 14 comprises 5 a fabric covering of appropriate texture which is shaped to conform to the features with which it cooperates. It is here shown as in the form of a rectangular sheet of fabric whose end portions 28 form the individual eye shields. Its central lower 10 edge portion is fashioned as indicated at 29 to form what may be designated as a nose rest or adapter. The numeral 30 merely designates the head encircling band or strap which is attached to the piece of fabric and serves to hold it comfortably in place. Obviously when this eye covering is in position as disclosed in Figure 1 it shields the eyes of the wearer from strong light and has a tendency to expedite and maintain sound sleep. 15 As before stated the units 13 serve to keep the mouth closed, to shape the chin by preventing drooping, and to incidentally prevent snoring. Obviously by keeping the mouth closed proper breathing through the nostrils is promoted. Then too as before indicated the head gear 12 which 20 is adjustable to the individual wearer is primarily used to hold the frame like ear adapters 21 in place which in turn embody the resilient plug retaining clips 22. Obviously these clips 22 are flexed or offset slightly as shown in Figures 2 25 and 3 in order to exert requisite resilient pressure against the ear plugs 23.

Attention is now invited in particular to the preferred types or forms of ear baffles or plugs utilized in conjunction with the retaining clips. 25 From Figures 10 and 11 it will be seen that each stopple comprises a hollow rubber body 31 of suitable elongated shape such as enables it to be conveniently inserted and forced lightly into the ear. The inner end 32 is rounded or of convex form so as to facilitate insertion and seating. The opposite or outer end is of segmental flat formation as indicated at 23 and at this end there is a lateral retaining lug 34 having a curved groove 35 to accommodate the adjacent 40 portion of the clip 22. The lug 34 also acts as a stop element and prevents the plug from being inserted too far. The plug is of an expandable and contractible type so that after it is inserted in the ear it may be expanded and securely held 45 against displacement. In accomplishing this I provide a screw threaded stud 36 having a curved head 37 which gives shape to the end 32 and provides the desired rigidity at this point.

The head is suitably and securely fastened to the rubber.

Engageable with this threaded stud is a hollow or sleeve bolt 38 having an external head 39 suitably shaped to facilitate convenient grasping and turning to draw the parts 36 and 38 together to expand the body 31. Incidentally the numerals 40 merely designate air ports or vents to facilitate release of air.

Obviously an expandable and contractible plug 10 of this type might well be used by itself though it is preferably used in conjunction with the clip 22 of the aforesaid adapter 21.

The gist of the idea is the provision of a lug equipped hollow rubber expandable and contractible ear stopple of appropriate shape and proportion equipped with internal screw threaded members cooperating in facilitating the expanding and contracting action.

A careful consideration of the foregoing description in conjunction with the illustrative drawings will enable the reader to obtain a clear understanding of the purpose, features and advantages, the explicit construction, and the invention as hereinafter claimed.

It is to be understood that minor changes in shape, size, relative portions, and materials may be resorted to in practice without departing from the spirit of the invention or the scope of the invention as now claimed.

Having thus described my invention, what I claim as new is:

1. A device of the class described comprising a vertically arranged bow for fitting over a portion of the top of the head of a user and a horizontally arranged bow for fitting around a portion of the back of the head, a depending substantially U-shaped frame for connecting each end of one bow with an adjacent end of the other bow, and an inwardly extending member connected 40 with one limb of the U-shaped frame and sloping for holding an ear plug in place.

2. Means for holding an ear plug in the ear of a person comprising a vertically arranged bow for fitting over the head of the user, and a horizontally arranged bow for fitting over a rear portion of the head, and a substantially U-shaped frame having the upper end of one limb connected to an end of one bow and the upper end of the other limb connected to an end of the other 50 bow, a portion of one limb of the U-shaped frame being bent inwardly and also bent toward the head to engage the plug.

LEO M. HOEY.
